ELECTRICAL WIRE PROTECTOR

Glenn V. Searer and Vernon A. Searer, both of 3401 S.
Nappanee St., Elkhart, Ind. 46514

Filed Oct. 31, 1972, Ser. No. 302,515

Term of patent 14 years

Int. Cl. D8—08

U.S. Cl. D8—263

Fig. 1

Fig. 3

Fig. 4

Fig. 5

Fig. 6

FIG. 1 is a perspective view of an electrical wire protector embodying the present design;

FIG. 2 is an elevational view of the end of the wire protector opposite the end shown in FIG. 1;

FIG. 3 is an elevational view of the side of the wire protector opposite that shown in FIG. 1; and

FIGS. 4, 5 and 6 are side elevational views of the present electrical wire protector.

We claim:

The ornamental design for an electrical wire protector, substantially as shown.
